Gypsum Company, Chicago, Ill., a corporation
of Illinois

Application July 30, 1932, Serial No. 626,898

16 Claims. (Cl. 189—85)

This invention relates to building constructions, and has reference more particularly to ceiling constructions for the correction of the acoustics in a room.

5 In the construction of ceilings for the purpose of absorbing sound and correcting acoustics in a room, it is customary to use a sound absorbing pad of fibrous material faced below with a perforated metal sheet which permits the sound to pass through the perforations and be absorbed in the fibrous pad. In such constructions the metal membranes should be easily erected by snapping them into place on the supporting runners by an upward movement from below. It is 10 also preferable to have the attaching means for holding the metal membranes in place, entirely free of the back face of the membrane so as not to cover up any perforations and thus make an unsightly appearance below, as well as not to reduce the sound passing efficiency of the membrane. It is also desirable to reduce the amount 15 of vertical space occupied by the acoustical unit to a minimum.

An object of this invention, therefore, is to 20 provide an acoustical ceiling comprising sound absorbing pads faced by perforated metal membranes in which a convenient means is supplied for quickly snapping the metal membranes into place on supporting structural runners.

Another object of the invention is to provide 25 an acoustical ceiling of the class described in which the attaching means for the perforated metal membranes is spaced apart from the inner face of the membrane so as not to cover up any of the perforations.

A further object of the invention is to provide 30 an acoustical ceiling construction in which the over-all height of the acoustical unit is kept to a minimum; also to improve building constructions in other respects hereinafter specified and 35 claimed.

Reference is to be had to the accompanying drawings forming a part of this specification, in which

40 Fig. 1 is a perspective view of one of the perforated membrane units,

Fig. 2 is a sectional elevation through a ceiling construction, including the membrane unit shown in Fig. 1,

45 Fig. 3 is a sectional, perspective elevation showing a portion of the acoustical ceiling construction on a large scale,

Fig. 4 is a sectional elevation through the ceiling construction taken adjacent a vertical building wall,

Figs. 5, 6, and 7 are sectional elevations through modified forms of the ceiling construction, and

Figs. 8, 9, and 10 are sectional elevations through the building construction taken on line 8—8 of Fig. 5, line 9—9 of Fig. 6, and line 10—10 5 of Fig. 7 respectively.

In the construction of our improved acoustical ceiling, a fibrous pad 12 of mineral wool, hair felt or other desired fibrous material, is suspended below a ceiling surface 13. Return bent 10 hanger straps 14 are secured to the ceiling 13 by means of toggle bolts 15, or other desired fasteners. Downwardly extending legs 16 are formed on the hanger 14 and terminate in U-shaped, opposed hooks 17 which engage opposite, 15 upper flanges 18 of a metal beam or runner 19 having lower outstanding flanges 20. The runner 19 is preferably constructed of a pair of channel strips with the webs thereof spot-welded together. Locking bars 21 extend across the space 20 between a pair of parallel runners 19 and terminate in hook ends 22 which engage the hanger legs 16 so as to force said legs together and securely grip the runner flanges 18. The bars 21 also serve to support the acoustical pad 12. 25

Sheet metal membranes 24 are suspended below the runners 19 and are provided with triangular shaped perforations 25 uniformly distributed over their area. If desired, the perforations may be any other suitable shape such as 30 square, round, elliptical, etc. The membranes 24 are preferably square in shape, but may be rectangular or other desired shape. Upwardly extending bevels 27 are formed around the perimeters of said membranes and the bevels terminate in upwardly extending flanges 28. When several of the membranes 24 lie with their flanges 28 in an abutting position, the bevels 27 give a pleasing tile-like appearance to the undersurface 35 of the ceiling.

In order to connect the membranes 24 to the runners 19, we provide inwardly extending flanges 30 on two opposite edges of each membrane, the flanges 30 terminating in upwardly extending flanges 31 which are offset from the 45 edge flanges 28 and preferably extend substantially vertically to the membranes 24 so as to form with the flanges 30, an L-shaped cross section. Each of the flanges 31 is provided with a plurality of apertures 33, and guide flanges 34 extend outwardly from two opposite edges of each aperture. A resilient clip 35 has one leg secured to flange 31 by a spot-weld 36, or other suitable fastening device. The clip 35 is provided with a resilient loop 37 which terminates 50

55 in a vertical leg 38 which terminates in a resilient loop 39 which terminates in a resilient loop 40.

in a spring flange 38 having an inwardly extending latching lug 39. The lug 39 is provided with a flanged cam surface 40 and a lower locking shoulder 41. As the metal membrane 24 is moved upwardly during the erection of the ceiling, the cam surface 40 engages the lower outer edge of the runner flange 20 and is deflected inwardly until it rises above said flange, and then the lug 39 snaps inwardly with the latching shoulder 41 seated snugly on top of the runner flange 20, thus securely attaching the membrane 24 to said runner 18. Adjacent the edge of a ceiling where the ceiling surface 13 meets a vertical wall 43, an L-shaped runner 44 is secured to the wall 43, as by nails 45. The runner 44 has an outstanding horizontal leg 46 which engages a clip on the flange 31 similar to clip 35. The runner 44 also has an offset upper flange 47 which engages with a downwardly extending lug 48 formed on the end of each of the cross bars 21.

It will be noted that with the form of attaching clip shown in Figs. 1 to 4, the axis of the loop extends substantially vertically, and all points of the attaching clip are down below the upper edge 25 of the flange 31, so that the vertical space necessary for the acoustical structure is reduced to a minimum. However, if desired, the attaching clip may be turned vertically as shown in Figs. 7 and 10, in which case the axis of the clip 50 extends substantially horizontally, said clip being secured to a membrane flange 51 which is somewhat wider than the flange 31. The clip 50 is provided with a resilient loop 52 which terminates in an outwardly inclined cam flange 53 which extends through an aperture 54 formed in the flange 51. An inwardly extending latching flange 55 is formed on the lower end of the cam flange 53 and serves to seat on top of one of the runner flanges 20.

In the form of construction shown in Figs. 6 and 9, a flat clip 57 has its upper end threaded between a struck-out strap 58 and a membrane flange 59. The upper part of the clip 57 has an arcuate locking edge 60 which is bent over on top of the strap 58 and is held in place by an arcuate, bent over, locking flange 61 formed on the upper edge of the membrane flange 59. The lower end of the clip 57 is provided with a cam flange 62 and a latching flange 63, similar to those shown in Fig. 7.

In the form of device shown in Figs. 5 and 8, a heavy wire clip 65 is bent into sinuous form 66 and is threaded through apertures 67 formed in a membrane flange 68. The lower part of the clip 65 is provided with a cam section 69 which extends through an aperture 70 formed in the flange 68, and said clip is also provided with a latching shoulder 71 which seats on top of one of the runner flanges 20.

We would state in conclusion that while the illustrated examples constitute practical embodiments of our invention, we do not wish to limit ourselves precisely to these details, since manifestly, the same can be considerably varied without departing from the spirit of the invention as defined in the appended claims.

Having thus described our invention, we claim as new and desire to secure by Letters Patent:—

1. In a building construction a metal runner having lower, outstanding flanges, a perforated metal membrane having upturned, peripheral flanges closely abutting the bottom of said runner flanges, an offset flange formed on said membrane flange, means on said offset flange for engaging the top of said runner flange so as to con-

nect said membrane to said runner and a fibrous pad above said membrane.

2. In a building construction, the combination with a runner having outstanding flanges, of a perforated metal membrane, an integral outstanding flange formed on said membrane and offset from the edge of said membrane so as to embrace the outside edge of a runner flange, a latching member secured to said offset flange and adapted to engage said runner flange so as to detachably secure said membrane to said runner, and a sound absorbing pad associated with said membrane.

3. A perforated membrane unit having outstanding flanges formed on opposite edges thereof, an L-shaped flange formed on one of said flanges and including an offset flange extending substantially vertically to said membrane, and means on said offset flange for detachably securing said membrane to a structural element.

4. An acoustical unit comprising a perforated, metal sheet membrane, an L-shaped flange formed on one edge of said membrane and including an offset flange extending substantially vertically to said membrane, and a resilient clip secured to said offset flange including a latch for attaching said membrane to a structural member.

5. An acoustical unit comprising a perforated, sheet metal membrane including an outstanding flange offset inwardly from the edge of said membrane, and a separate attaching clip having a resiliently held latch, said clip being secured to said offset flange below the top edge of said flange.

6. An acoustical unit comprising a perforated, sheet metal membrane including an outstanding flange offset inwardly from the edge of said membrane, an attaching clip secured to said offset flange, said clip having a resilient loop having the axis thereof extending substantially parallel to the upper edge of said offset flange, and a latch on said clip for attaching said membrane to a structural member.

7. An acoustical unit comprising a perforated, sheet metal membrane including an outstanding flange offset inwardly from the edge of said membrane, an attaching clip secured to said offset flange, said offset flange having an aperture, and a latching member resiliently connected to said clip and extending through said aperture for attaching said membrane to a structural member.

8. An acoustical unit comprising a perforated, sheet metal membrane including an outstanding flange offset inwardly from the edge of said membrane, a strap struck out from the metal of said flange, and a resilient latching clip secured to said offset flange by said strap.

9. An acoustical unit comprising a perforated, sheet metal membrane including an outstanding flange offset inwardly from the edge of said membrane, a resilient clip secured by spot welding to said offset flange, and a latching member on said clip for attaching said membrane to a structural member.

10. An acoustical unit comprising a perforated, sheet metal membrane including an outstanding flange offset inwardly from the edge of said membrane, an attaching clip secured to said offset flange, said clip having a resilient loop having the axis thereof extending substantially perpendicular to the outer edge of said offset flange, and a latch on said clip for attaching said membrane to a structural member, all parts of said clip

lying inwardly of the outer edge of said offset flange.

5 11. An acoustical unit comprising a perforated, sheet metal membrane including an outstanding flange offset inwardly from the edge of said membrane, said offset flange being provided with a plurality of apertures, a resilient wire clip threaded through said apertures for rigid engagement with said flange, and a latching member formed on said clip for engagement with a supporting structural member.

10 12. An acoustical unit comprising a perforated, sheet metal membrane including an outstanding flange, an aperture being formed in said flange, guide flanges adjacent said aperture, and a resilient clip secured to said outstanding flange and having a latch member extending through said aperture adjacent said guide flanges.

15 13. In a membrane surface building construction, a flanged support, a membrane unit, a substantially L-shaped flange at one edge of said membrane, said flange comprising a part substantially parallel with said membrane and a part substantially perpendicular to and offset inwardly relative to said membrane edge, and a clip on said offset flange part for connecting said membrane to said flanged support, said clip engaging the upper face of a support flange and forcing the horizontal flange part into engagement with the lower face of said support flange.

20 14. In a membrane surface building construction, a plurality of parallel flange supports, individual membrane units in edge to edge relationship below said supports, substantially L-shaped

flanges at abutting edges of said membranes, each of said flanges comprising a part substantially parallel with said membranes, and a part substantially perpendicular to and offset inwardly relative to said membrane edges, and clips at spaced intervals on said offset flanges for connecting said membranes to said flange supports, each of said clips engaging the upper face of a support flange and forcing the horizontal flange part of said membrane unit into engagement with the lower face of said support flange, whereby said membrane units are maintained in close edge-to-edge relationship as well as into close engagement with said flange supports.

25 15. A membrane unit adapted for building construction, comprising a substantial face portion, a flange at the edge of said face portion having an aperture therein, a resilient clip attached to the inner face of said flange, and a latching portion on said clip extending through said aperture and adapted for engagement with support means.

30 16. A membrane unit adapted for building construction, comprising a substantial face portion, a flange at the edge of said face portion having an aperture therein, a clip comprising a resilient loop and having one end attached to said flange, and a latching portion on the other end of said loop and extending through said aperture and adapted for engagement with support means.
